[57] ABSTRACT

A swimming aid for children comprising a vest-like harness which includes arm holes and a short body-embracing portion and which is arranged to be put on and removed over the head; an annular retaining sheath fast with the body-embracing portion; and an inflatable tube trapped in the sheath in breast embracing position.

1 Claim, 2 Drawing Figures

PATENTED JUN 28 1974

3,820,178

Fig 2.

SWIMMING AIDS

This invention relates to swimming aids for children.

It is well known for children to use an inflated tube for supporting themselves in the water during swimming or playing. A tube normally suffers from the disadvantage that a child can slip through the tube and lose its grip thereon, or tip over and up-end with its head in the water, a position from which it is difficult to recover. This could have fatal results for a child who is unable to swim.

It is also known to provide inflatable arm bands for supporting a child above water. Such arm bands are also not entirely satisfactory and can slip off the arms of a child wearing them if they are not properly inflated or fitted. It is also possible for such arm bands to be taken off unnoticed by a child wearing them.

It is an object of the present invention to provide an improved swimming aid with which the above disadvantages are avoided or at least minimised.

According to the invention a swimming aid comprises a vest-like harness which includes arm holes and a short body-embracing portion and which is arranged to be put on and removed over the head; an annular retaining sheath fast with the body-embracing portion; and an inflatable tube trapped in the sheath in breast embracing position.

With the swimming aid according to the invention, the tube is removably attachable to the body of a person by putting on the harness over the head and inserting the arms through the arm holes of the harness. There is little danger of the wearer losing his grip on the tube. With a snugly fitting swimming aid, the tube is located in breast embracing position under the arm pits when the harness is on the wearer.

It has been found that the centre of gravity of a normal human body is well below the breasts and the arm pits so that with a snugly fitting swimming aid according to the invention, there is a natural tendency for the head of the wearer to be supported above water.

Preferably, the body embracing portion of the harness is substantially co-extensive with the inflated tube in a direction longitudinally along the body of a wearer.

It has been found that with the inflated tube located in breast embracing position under the arm pits and with a harness having a body-embracing portion which is substantially co-extensive with the inflated tube, it is for all practical purposes impossible for the wearer to remove the harness himself without assistance while the tube is inflated. This enhances the safety of a swimming aid according to the invention from the point of view of small children who are unable to swim.

Removal of the harness may further be inhibited by the material of the harness adhering to the body of the wearer when the harness is wet.

Preferably, the harness is made of a resilient material so that it hugs the body of a wearer.

The tube may be of substantially circular configuration when inflated. With a snugly fitting swimming aid incorporating a circular tube, the tube has to be distorted into elliptical shape to slip it over the shoulders of a wearer when it is put on and removed. This further complicates removal of the harness without assistance while the tube is inflated.

The tube may be provided with a valve extending through the retaining sheath. The valve is preferably of the non-return type used on the inner tubes of the wheels of motor vehicles, in which the valve closure member has to be displaced inwardly against the inflation pressure in the tube to cause deflation.

Preferably, also the valve is adapted to be located at the back of a wearer.

The harness may have a form such that it can only be worn comfortably one way in which the valve is located at the back of the wearer. This would discourage the putting on of the harness back-to-front with the valve located at the front of the wearer.

A preferred embodiment of the invention will now be described by way of example with reference to the accompanying drawings in which:

FIG. 1 is a perspective view of a swimming aid according to the invention.

FIG. 2 is a section on the line 11-11 in FIG. 1.

20 The swimming aid comprises vest-like harness 1 of resilient, body hugging material, such as so-called stretch nylon or the like. Harness 1 includes head hole 2, arm holes 3, shoulder straps 4 and short body-embracing portion 5. In effect, the harness 1 is in the nature of the upper portion of a girl's two-piece swim suit having a circumferentially continuous breast embracing portion. No fastening devices, such as buttons, hooks, laces or the like, are provided nor required.

25 A length of material which is integral with the lower end of body-embracing portion 5, is wrapped round circular pneumatic tube 6 and is stitched to body portion 5 around its entire circumference at 10 to form an annular tube retaining sheath 7 which totally encloses and traps tube 6 in breast embracing position. As shown in FIG. 1, the tube 6 is located in breast embracing position under the arm pits of a wearer when the harness fits the wearer snugly. The circular tube 6 can fit snugly but comfortably round the chest of the wearer.

30 35 Tube 6 is provided with a conventional valve 8 of the non-return type commonly used on the inner tubes of the wheels of motor vehicles, in which the valve closure member has to be displaced inwardly against pneumatic pressure in the tube to cause deflation. Valve 8 extends through sheath 7 and is provided with a screw cap 9. As shown in FIG. 1, valve 8 is adapted to be located at the back of the wearer so that it is impossible or at least difficult for the wearer to reach the valve. For all practical purposes it is impossible for the wearer to unscrew cap 9 and actuate valve 8 to deflate tube 6.

40 45 50 55 60 65 Where the harness 1 and tube 6 fits the wearer snugly, it is necessary for the wearer to stretch both arms upwardly above his head in order that the harness may be pulled on and off over his head. With the arms stretched above the head, tube 6 has to be distorted into elliptical formation to allow it to pass over the shoulders of the wearer. The resilient material of harness 1 hugs the body of the wearer and inhibits distortion of the circular tube to the elliptical shape necessary for removal.

It will be appreciated that for all practical purposes, a child wearing the swimming aid will not be able to deflate the tube and will not be able to remove the harness without assistance.

With tube 1 located in breast embracing position under the arm pits as shown in FIG. 1, there is a minimum of interference with the movements of the wearer

and there is a natural tendency for the head of a wearer with a normal body to be supported above the water because of the centre of gravity of the wearer being located below the tube 6. A swimming position can be obtained quite easily by leaning the upper portion of the body forwards or backwards and kicking with the legs. When diving or falling head first into deep water the head will immediately rise above the water level.

Children who cannot swim can play unattended around swimming pools and on beaches when wearing a swimming aid according to the invention. The danger of a child removing the swimming aid unnoticed is reduced to a minimum.

A swimming aid according to the invention is particularly applicable for use by small children between the ages of 6 months and 8 years, but could be used by all age groups. It is important that the correct size of swimming aid be selected for each wearer so that the harness fits the wearer snugly and locates the tube in the correct breast embracing position under the arm pits.

A swimming aid according to the invention is also suitable for use by paraplegics, or poliomyelitis victims requiring water or swimming therapy. Where an abnormal body has an unbalanced weight distribution, weights may be provided on the body of the wearer below the tube. Thus, a weighted belt may be provided around the waist, ankles or any other part of the body below the waist.

A swimming aid according to the invention is simple in design and construction, yet effective in use.

It will be appreciated that many variations in detail are possible without departing from the scope of the appended claims.

I claim:

1. A swimming aid for children, comprising a vest-like harness of resilient, body hugging material, the harness having arm holes and a short circumferentially continuous chest-embracing portion and the harness being arranged to be put on and removed only over the head; an annular retaining sheath fast with the chest-embracing portion of the harness; a single circumferentially continuous and annular inflatable tube trapped in the sheath in a position in which it is located under the arm pits and embraces the chest only of a wearer, the inflated tube being substantially co-extensive with the chest-embracing portion of the harness in a direction longitudinally along the body of a wearer so that the harness extends substantially only as far down the body of the wearer as does the tube, the tube normally being of circular configuration when inflated but having to be distorted from the circular configuration to pass over the shoulders of a wearer on which the swimming aid fits snugly; and a valve on the tube which extends through the retaining sheath and is arranged to be located at the back of a wearer.
